UNITED STATES PATENT OFFICE.

MARIE JOSEPH HENRI JOLY, OF PARIS, FRANCE.

CHRONOPHOTOGRAPHIC APPARATUS.

SPECIFICATION forming part of Letters Patent No. 569,875, dated October 20, 1896.

Application filed June 5, 1896. Serial No. 594,437. (No model.) Patented in France August 26, 1895, No. 249,875.

To all whom it may concern:

Be it known that I, MARIE JOSEPH HENRI JOLY, a citizen of the Republic of France, and a resident of Paris, (Seine,) in said Republic, 5 have invented certain new and useful Improvements in Chronophotographic Apparatus, (for which a patent has been secured in France, No. 249,875, dated August 26, 1895,) of which the following is a full, clear, and exact description.

This invention relates to a chronophotographic apparatus whereby a large number of photographs, each very clear, may be taken within a given time. It may serve also as a 15 kinetoscope.

In the accompanying drawings, which form part of this specification, by way of illustrating the invention, an apparatus constructed in accordance with the said invention is represented.

Figure 1 is a vertical section of such apparatus; Fig. 2, a front elevation of the same, and Figs. 3 and 4 detail views of the means for producing the arrest of the film at the 25 moment desired.

The apparatus consists of a wooden box, in the interior of which are two metallic frames that support the working parts to be described.

30 The control of the apparatus is obtained by the aid of a crank A, connected with the wheel B. This latter operates a pinion D, keyed on the shaft E, through a chain C. A roller D' enables the chain to be stretched at will. The shaft E carries a pinion F, which operates the wheel G through the intermediates G' G''. On the shaft of the wheel G is mounted a roller H, provided with two circles of teeth on its periphery, these teeth enclosing 35 gaging holes formed along the whole length of the film-band I. A pressure-roller H' holds the film against the roller H, which insures its engagement. A spring acts upon the arm which supports the axle of roller H'. When 40 the roller H turns, it carries along the film, which is wound upon the spool J. After leaving the roller H the film passes between two rollers K K', which hold it in the desired position. The film then descends vertically and 45 enters the dark chamber L. At its exit from the dark chamber it passes over the roller M and through the interior of the frame N, which

is supported by rocking arms N'. From the frame N the film passes between the two rollers O and O', over the toothed roller P, over 55 the roller Q, and is finally wound upon the spool R.

The shaft E carries a pinion S, which, through the intermediate S', drives the wheel T, fast on the shaft of the roller P. The movement is given to the spool R by a spring in the barrel U. This barrel is for this purpose provided with a wheel U', which drives the shaft of the spool R through the pinion U''.

To explain the operation of the apparatus, 65 it will be supposed that the film has been introduced into its working position, and the operation will be described as it would then take place. The shaft E being moved, the roller H turns and unrolls the film from the spool 70 J. When the photograph has been taken, the crank-disk V acts upon the frame N through the connecting-rod X, moving it about the axis of oscillation N'' of the arms N' and forcing it to approach the front of the apparatus. 75 The film, which is caught in the frame N, is carried along, and since its lower part is held by the teeth of the roller P it cannot be drawn back, and the portion which has been printed will be obliged to pass out of the dark chamber, being replaced therein by a new and unexposed portion of the film. The shaft E continuing to turn, the frame N returns rearward, and the loop which it formed in advancing being no longer held can be taken 80 up by the roller P. The roller H for its part will have unrolled from the spool J a length of film corresponding with that which has been wound below on the spool R.

85 Before commencing the operation, at the 90 moment when the film is introduced into the apparatus a loop is formed by hand between the roller H and the rollers K K', and as the same length is wound upon the spool R as is unrolled from the spool J this loop will 95 maintain itself during the whole time the apparatus operates. It hence results that as the roller P does not pull upon a tight film the latter is not liable to be torn apart.

At the beginning of the operation the 100 spring in the barrel U is about half-wound. In order that the tension of this spring may be maintained, (for this it is which produces the rotation of the spool R,) a wheel is placed

on the axle of the roller P, and this wheel drives the pinion Y' through the chain Y. On the axle of pinion Y' is another pinion Z, which meshes with the wheel Z', whereby the 5 spring is wound. Thus during the working of the apparatus the tension of this spring is kept constant.

The shutter a is mounted in a shaft b, which carries a worm-wheel c, that is engaged 10 by the endless screw d on the shaft E.

In order that the film may be easily moved at the time of its entrance into the dark chamber and may also be arrested during the exposure, a hinged leaf e, Figs. 3 and 4, 15 is arranged a little above the entrance to the dark chamber, and this hinge is provided with a pin e', which is movable in a slot in the upper arm of a lever f, fulcrumed on the stud g. In the lower arm of this lever there is a 20 slot in which works a pin on the end of the bar h, that is fastened to the strap of the eccentric i. This eccentric is fast on the shaft E. At the moment when the frame N advances to draw down the film which has been 25 exposed the bar h also advances, and the lever f is rocked on its fulcrum and withdraws the leaf e from the plate j, against which it has clamped the film. This plate is provided with a velvet band, which prevents the film 30 being injured by rubbing. This plate j is removable, as shown in Fig. 3, so that the velvet band can readily be replaced when it is worn or when it becomes clogged with powder.

During all the time the frame N is advancing 35 toward the front part of the apparatus the leaf e remains withdrawn from the plate j, and nothing, therefore, opposes the free movement of the film. As soon as the frame N is at the end of its course the eccentric 40 brings forward again the lever f and causes the leaf e to bear against the plate j, and the film is stopped.

It will thus be seen that if the film tended 45 to continue its downward movement it would be arrested by the leaf e, and besides the pressure of the leaf against the plate j permits the roller P to keep the film stretched constantly in the dark chamber.

When the film is at rest, one of the 50 openings in the shutter comes between the dark chamber and the objective. The film then is printed or exposed at the moment in which it is at rest. A diaphragm of variable opening is placed in the dark chamber. In small 55 apparatus the roller H may, if desired, be suppressed. The film would then be unwound by the action of the frame N.

When the apparatus is to serve as a kinetoscope, the back of the dark chamber is 60 placed by a translucent plate, the film is unrolled, as before explained, and by placing a sufficient source of light provided with a reflector or condenser behind the apparatus the

image which may be on the film can be received on the screen. This image cannot be 65 projected except when the film is at rest, for, as observed above, it is only at such time that one of the openings in the shutter is in front of the dark chamber and permits the luminous rays to pass through the objective. By 70 reason of the system of supporting and shifting the film this may be of very great length and consequently of a considerable weight. The frame N, which produces the shifting of the film, does not have to act directly on the 75 spool, since there is constantly a certain length of film unrolled in advance. This frame then is not required to produce itself the rotation of the spool. In certain cases a single toothed wheel might suffice, provided 80 it is of sufficiently large diameter. The two spools being then placed on the same side of the apparatus, the roller-teeth may produce on one hand the unwinding and on the other the rewinding of the film. The frame N can 85 (without departing from the invention) be replaced by an eccentric roller which will communicate to the film the same movement as the frame.

I claim as my invention or discovery— 90

1. In an apparatus of the kind described wherein a film having perforations at regular intervals therein is employed, two toothed rollers, the teeth thereon engaging perforations in the film, one for unrolling and the 95 other for rewinding the film, means for rotating the rollers at a uniform continuous movement, means for forming a loop in the film in advance of the dark chamber, and a frame reciprocating at right angles to the 100 normal line of feed and acting to periodically form a loop in the film after it leaves the dark chamber, whereby the film is passed through said chamber by an intermittent movement, substantially as described. 105

2. In an apparatus of the kind described, means for unrolling and means for rewinding the film at a uniform continuous movement, means for forming a loop in the film in advance of the dark chamber, and a frame reciprocating at right angles to the normal line 110 of feed of the film and acting to periodically form a loop therein after it leaves the dark chamber, whereby the film is passed through said chamber by an intermittent movement, 115 and a clamp or gripping device located immediately in advance of the dark chamber and actuated to hold the film during intervals of exposure, substantially as described.

In testimony whereof I have signed this 120 specification in the presence of two subscribing witnesses.

MARIE JOSEPH HENRI JOLY.
